UNITED STATES PATENT OFFICE

97,771

DESIGN FOR A TEXTILE FABRIC OR SIMILAR ARTICLE

Lina Hartmann, New York, N. Y., assignor to Milton M. Wolf, doing business as Wolf Silk Company, New York, N. Y.

Application November 12, 1935, Serial No. 59,502

Term of patent 3½ years

To all whom it may concern:

Be it known that I, Lina Hartmann, a citizen of the United States of America, residing at 500 West 114th Street, New York, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines

on the drawing outline substantially a design unit, which unit is repeated in regular succession as indicated by the extensions beyond the unit boundaries.

I claim:

The ornamental design for a textile fabric or similar article as shown and described.

In testimony whereof I have signed this specification.

LINA HARTTMANN.
